SHUTTLE FOR LOOMS

Abraham Cohen, Amsterdam, Netherlands

Application January 6, 1933, Serial No. 650,566
In Germany January 11, 1932

17 Claims. (Cl. 139—196)

The invention relates to a special construction of shuttles for looms as well as to the construction of the bobbins and holding spindles of such shuttles.

5 The ordinary loom shuttles fill up the maximum space which can be accepted for the shed in the case of a loom, only very scantily, and consequently also permit only a bobbin having a quantity of yarn, which is slight in proportion to this 10 shed-space, to be accommodated in the shed. This defect is, according to the invention, remedied in a simple manner by the loom shuttle being approximated in its cross-section to the size of the shed. The maximum degree of approximation results, moreover, if the cross-section of the shuttle is conformed also in its shape to the shape of the shed, it being shaped preferably in the form of a trapezoid.

With such a shuttle approximated to the shed 20 in size and, if desired, in shape, it is possible to accommodate in the shed-space which is present, and which in some circumstances can be angularly widened, a materially greater quantity of 25 yarn and consequently to attain a considerable extension of the running time of the shuttle and correspondingly a reduction of the number of 30 shuttle-changes. On the other hand it is possible in the case of the given quantity of yarn, to accommodate this quantity in a shed having a 35 smaller angle than hitherto. These favourable effects may according to the invention be further materially increased by there being employed for the shuttle not the ordinary round bobbin but a bobbin the body of the yarn on 40 which is conformed to the shape of the shed by having an elongated cross-section. It is advantageous so to shape the cross-section of this flat bobbin that it fills up as extensively as possible the shuttle assimilated to the shape and to the 45 size of the shed.

Such flat bobbins can be obtained from round bobbins by changing them by winding or by changing them by pressure. The transformation of round into flat bobbins can according to 45 the invention be in an especially simple manner facilitated, when a holding spindle is employed, by said holding spindle being turned to account as means for this object. For this purpose the spindle is according to the present invention given such an elongated shape in cross section 50 that the body of yarn of a round bobbin put on it is converted positively into a flat shape. This elongated cross-section of the spindle may conform to the shape of the shed and for example 55 may be of an oval shape, so that the flat bobbin

produced by the spindle is made of a cross-section assimilated to the shape of the shed.

The conversion of a round bobbin into a flat bobbin with the aid of the shuttle spindle may according to the invention be effected simply by 5 placing the bobbin on the spindle if the elongated cross-section of the spindle is of such dimensions that the cross-section of the body of the 10 yarn on the bobbin is stretched into the desired elliptic or other flat shape merely by being pushed on. The spindle may also be composed of two or 15 more parts which are movable relatively to one another and which on being swung to and fro bring about an alteration of the cross-section of the spindle, a feature which is well known per se 20 as a means for attaining a firmer adherence of the bobbin on the spindle, and moreover the transformation of the bobbin may according to 25 the invention be effected in an especially convenient and reliable manner by the swinging motion of the parts of the spindle being made full 30 use of for this object. For this purpose, according to the invention, the alteration of the cross-section of the spindle having two or more parts on the latter being swung to and fro extends over 35 such a great extent of the spindle and is made to be of such a great amount that the body of yarn on a bobbin mounted on the swung out spindle is positively converted by the swinging-in movement into a shape flatter relatively to its initial 40 cross-section. The spindle may moreover be suitably so mounted in the shuttle that the greater diameter of the flat cross-section given to the 45 bobbin lies approximately in the direction of the middle of the shed.

The relative movability of the parts of the spindle during the swinging movement may according to the invention be attained by means of eccentricities whereby considerably spread angles between the parts of the spindle can readily be attained, as is necessary for an alteration of the 50 cross-section of the spindle transforming a body of yarn. An extraordinarily simple and effective form of construction of a multiple-part spindle according to the invention is produced by the 55 parts of the spindle being freely displaceable relatively to one another at their outer ends and being mounted relatively to one another at their other ends in such a manner that on the spindle being swung in its cross-section assumes the shape corresponding to the desired shape of the flat bobbin.

Moreover it is advantageous for the accommodation, in the loom shuttle, of the swinging mechanism of a spindle which is capable of being 55

swung in and out, to provide the back or front walls of the shuttle according to the invention with an opening for the passage therethrough of the spindle and to permit the passage in and out of the parts of the spindle to take place in a plane transverse to said back or front wall. In that way a spreading apart of the parts of the spindle can be attained in a simple way in a direction approximately parallel to the bottom of the shuttle or in the direction of the middle of the shed. There is also obtained the advantage, compared with the otherwise usual introduction of the spindle through the upper side of the shuttle, that the yarn is better protected by the upper side of the shuttle, which can be closed entirely or to a great part and is reliably prevented during the weaving operation from protruding from the shuttle.

The bobbin which is to be put on the divided or undivided spindle may be wound upon an inner tube of cardboard or other material by means of which it is placed on the spindle. But it may also be made without such an inner tube. Also in the case of a shuttle which does not possess a divided or undivided spindle, a bobbin with an inner tube as well as a bobbin without such an inner tube can be used in the manner of the invention.

The drawings illustrate the loom shuttle according to the invention by way of example in several constructional forms. Fig. 1 shows in cross-section a rectangular shuttle with a holding spindle which is elliptic in cross-section and Fig. 2 is a representation of a detail of this spindle. Fig. 3 illustrates in cross-section a shuttle which is constructed in the shape of a trapezoid and has a holding spindle of oval cross-section. Figs. 4, 5 and 6 show in part sectional front and side elevation and in cross-section a loom shuttle with a multiple-part holding spindle, the parts of which are displaceable relatively to one another by means of eccentrics. Figs. 7 and 8 reproduce in front and side elevation a shuttle likewise provided with a multiple-part spindle, in the case of which shuttle the relative displacement of the parts of the spindle is effected by means of a wedge. Figs. 9, 10 and 11 show in front and side elevation and in cross-section a further constructional form of a loom shuttle having a spindle which is variable in cross-section when swung to and fro, in the case of which spindle this variation in cross-section is brought about merely by means of a special relative position of the points of oscillation of the parts of the spindle. Figure 12 shows in cross-section a loom shuttle used as means for transforming a body of yarn of a round bobbin into a flat bobbin.

According to Fig. 1 the shuttle *a* is approximated to the size of the shed, which is formed by the warp threads *b*, *c* between which a certain angle is formed, by its cross-section having the shape of an elongated rectangle, which fills out the shed to a much greater extent than a shuttle *a*¹ of the usual dimensions, which are indicated in dotted lines. The yarn body *d* of the bobbin accommodated in this shuttle *a* possesses an elliptic cross-section which utilizes the cross-section of the shuttle and consequently the shed space to a more favourable extent than the ordinary round bobbin *d*¹, shown in dotted lines, in its shuttle *a*¹. When a spindle is provided for holding the flat bobbin *d* said spindle also is elliptic in cross-section. This spindle *e* may have a cross-section tapering towards one end

in order to enable the bobbin to be placed more readily on the spindle, or, in order, as for example Fig. 2 shows, that the shape of the spindle may be suited to the form of the tube of the bobbin. The bobbin *d* is in the first place wound as a round bobbin, for example, on a cardboard tube of a circumference equal to the elliptic cross-section of the spindle *e* and automatically becomes flattened on being pushed on to the spindle *e*.

According to Fig. 3 the shuttle *a* is approximated not only in size but also in shape to the shed *b*, *c*, its cross-section possessing the shape of a trapezoid filling up the shed as much as is practically possible. The shuttle-spindle *e* has a cross-section which is suited to the triangular shape of the shed and the longitudinal centre-line of which coincides with the centre-line *x*-*y* of the shed and said cross-section determines the corresponding oval cross-section of the bobbin *d* mounted on said spindle. The flat bobbin *d* makes the most favourable use of the available interior space of the shuttle *a* and consequently also of the shed and it is consequently able to contain a considerable quantity of yarn. The bobbin *d* may both in the case of Fig. 2 and in that of Fig. 1 also be made without an inner cardboard tube and be put on the spindle *e*. Moreover the spindle *e* may be independent of the shuttle and not be inserted in the latter until after the bobbin has been put on.

According to Figs. 4 to 6 the spindle of the shuttle *l* consists of three parts *2*, *3*, *4* of which the two outer parts *2*, *3* are similar to one another and taper towards their external ends to a point, the middle part *4* tapering inwards. The middle part *4* is revolvable about the pivot-pin *5* mounted in the shuttle casing *l*, while the two side parts *2*, *3* of the spindle are guided, with the aid of the pins *12*, *13* connected to them, on arc-shaped slots *22*, *23* in the shuttle-casing *l* and are displaceable at their inner ends along the eccentrics *32*, *33* mounted fixedly on the stationary pivot-pin *5*. The three spindle parts *2*, *3*, *4* are held together at their outer ends by means of a cap *6* put on them. The eccentrics *32*, *33* have a curved contour line, the curvature radius of which decreases progressively from the vertical line to the horizontal line and the spindle parts *2*, *3* are in the form of wedges decreasing in their cross section towards their outer ends while the spindle part *4* is formed as a wedge increasing in its cross section towards its outer end. Consequently the spindle parts *2*, *3*, when the spindle is swung about the pivot pin *5* in the shuttle *l* out of the swung-out position indicated in Fig. 5 in dotted lines into the position represented in full lines, become shifted outwards relatively to the middle part *4* and thereby positively transform the cross-section of the spindle—compare Fig. 6—from a contour-line permitting a round bobbin *7*, *9* to be pushed on loosely practically over the whole length of the spindle, into the flat shape *8* suited to the shuttle. This is accomplished because the eccentrics *32* and *33*, during the swinging movement from dotted line to full line position, move the parts *2* and *3* away from the shaft *5* while the part *4* is held a constant distance from said shaft so that the parts *2* and *3* are wedged apart by their longitudinal movement of the part *4*. In this manner by simply swinging the spindle *2*, *3*, *4* into the shuttle *l* the round bobbin *9* can be transformed positively into the flat bobbin *10*. The swinging of the spindle in and out takes

place in this case through the upper wall 14 of the shuttle.

In the case of the arrangement according to Figs. 7 and 8, of the three parts 15, 16, 17 which taper towards their outer ends the two outer ones 15, 17 are revoluble about a pivot pin 18 which is fixedly mounted in the shuttle 1 and on which an eccentric 19 is fixedly mounted by means of which the middle part 16 of the spindle guided 10 with the aid of the pin 20 in a slot 21 in the shuttle casing is shifted relatively to the outer parts 15, 17 of the spindle when the latter is swung in and out. By means of this shifting of the middle part 16 the outer parts 15, 17 of the 15 spindle, which are connected together by means of springs 24, 24', are so spread apart when the spindle is swung into the shuttle, that by a suitable alteration of the cross-section of the spindle, which alteration extends over the whole length 20 of the spindle, a round bobbin put on said spindle in its swung out position is transformed positively into a flat bobbin.

In the case of the weaving shuttles according to Figs. 9 to 11 the spindle consists of two parts 25, 26 the outer ends of which are freely displaceable relatively to one another and moreover are held together by means of a cap 27 accommodated on one part 26, while the inner ends of these parts 25, 26 are mounted with the aid of fixed axles 33, 36, about which the whole spindle can be swung in and out through the back wall 28 of the shuttle. The two axles 33, 36 are arranged in such relative positions in the shuttle that the angle formed between the parts 25, 26 of the 35 spindle is increased when the spindle is swung into the shuttle and consequently the round bobbin 29 put on the spindle in the swung out position of the latter is positively converted into the flat bobbin 30.

40 The plane in which the parts 25, 26 of the spindle are swung may be parallel to the bottom surface 31 of the shuttle or coincide with the central plane X-Y of the shed or the parts 25, 26 of the spindle situated in the middle plane 45 X-Y of the shed be arranged on a special carrier 34, which itself is capable of swinging parallel to the bottom 31 of the shuttle and is indicated in Fig. 11 in dotted lines. Moreover the parts of the spindle which are movable relatively to one another may, if the spindle is capable of 50 being removed completely from the shuttle, be arranged even separately from the shuttle for example, on a separate support, and be introduced into the shuttle after the bobbin has been 55 put on and been transformed, any sort of holding or clamping means whatever being provided for this purpose.

The flattened bobbin may be provided for in the shuttle not only parallel to the surface of 60 the bottom of the shuttle or in the direction of the central plane of the shed but also in another direction, for example, in any direction lying between these two planes. Also the swinging movement can take place in each of these directions. 65 The direction in which the flat bobbin lies in the shuttle, must not determine the direction of the swinging out movement. Moreover the divided or the undivided spindle may according to the invention instead of being employed for converting 70 round into flat bobbins also be otherwise employed for transforming the yarn-bodies of bobbins, for example, in order to convert an angular bobbin cross-section into a cross-section limited in shape by curves, for which it is merely necessary for the cross-section of the spindle to be of

a corresponding shape. Further, when spindles having two or more parts are employed, the relative motion of these parts, by means of which motion the transformation of the bobbins is brought about, can also be attained without 5 swinging the spindle by changing the relative position of the parts of the spindle by means of inserted wedges or similar means or merely by displacement.

Finally, in the case of tubular cops or in general 10 in the case of bobbins without interior tubes and with thread unwound from the interior of the bobbin, the transformation of the cross-section of the body of yarn may be attained, without having recourse to a holding spindle, simply by 15 the interior of the shuttle, which serves to house the yarn, possessing an elongated cross-section as shown in Fig. 12 where the cross section of the shuttle 38 possesses the shape of a trapezoid and by the body of yarn being converted, from an 20 initial diameter exceeding the width or height of this cross-section, as indicated in Fig. 12 by the dotted circle 39 into a shape approximating for example the shape of the shuttle, as indicated in Fig. 12 by the contour line 40, by being forced 25 into the interior of the shuttle.

I claim:

1. A shuttle for looms comprising a casing having an opening in one side, a spindle consisting of taperingly arranged parts movable longitudinally one with respect to another, spindle supporting means in the shuttle at one end of the spindle and supporting the spindle for swinging movement at its free end into and out of the casing through the opening, said spindle supporting means including means causing longitudinal movement of the spindle parts relative to each other during swinging movement and thereby causing lateral spreading of the spindle parts as they are swung into the casing, and a cap carried 40 by the free end of one of the spindle parts and enclosing the free end of the spindle to hold the parts together.

2. A shuttle for looms comprising a casing having an opening in one side, a spindle consisting of 45 a pair of members converging uniformly toward each other from end to end and contacting at their point of convergence, spaced pivot members in the casing parallel to the open casing side and having the spaced ends of the spindle members 50 mounted thereon, and a cap on the free end of one of said spindle members and engaging over the free end of the other spindle member to hold said free ends from spreading.

3. A shuttle for looms comprising a casing having an opening in one side, a shaft fixed across one end of the casing parallel to the open casing side, a spindle member of bluntly wedge shape and having its smaller end pivoted on the shaft to swing at its free end through said opening, a 60 pair of spindle members supported against the sides of the first mentioned member for sliding movement longitudinally thereof, and to swing with said first mentioned member as the latter swings on the shaft, and means for effecting 65 longitudinal movement of the pair of members on the first mentioned member as the latter swings.

4. A shuttle for looms comprising a casing having an opening in one side, a shaft fixed across one end of the casing parallel to the open casing 70 side, a spindle member of bluntly wedge shape and having its smaller end pivoted on the shaft to swing at its free end through said opening, a pair of spindle members supported against the sides of the first mentioned member for sliding 75

- movement longitudinally thereof, and to swing with said first mentioned member as the latter swings on the shaft, and a pair of eccentrics fixed to said shaft on opposite sides of the pivot connection of the first mentioned member, said eccentrics engaging the adjacent ends of the pair of members and shaped to cause movement of the pair of members towards the larger end of the first mentioned member as the latter is swung into the casing.
5. A shuttle for looms comprising a casing having an opening in one side, a shaft fixed across one end of the casing parallel to the open casing side, a spindle member of bluntly wedge shape and having its smaller end pivoted on the shaft to swing at its free end through said opening, a pair of spindle members tapered in a direction opposite the taper of the first mentioned member and supported against the sides of the first mentioned member for sliding movement longitudinally thereof, and to swing with said first mentioned member as the latter swings on the shaft, and means for effecting longitudinal movement of the pair of members on the first mentioned member as the latter swings.
10. A device for flattening the shape of a body of yarn of a round bobbin for loom shuttles, comprising a rod as a holding spindle for bobbins having an elongated cross-section, and a body of yarn of a round bobbin having an interior diameter smaller than the width of the cross-section of the rod, the said bobbin being transversely distorted by reason of the elongation of the said rod.
15. A device for flattening the shape of a body of yarn of a round bobbin, particularly of a loom shuttle or the like, comprising a rod as a holding spindle for the body of yarn, said spindle having a cross-section of greater width than height, the said spindle being operative when a body of yarn is pushed upon it to distort the round body of yarn and form it into a body having greater width than height.
20. In an expansible spindle for loom shuttles comprising at least two parts movable relatively one to the other, a body of yarn of a bobbin having an interior hollow space applied to the spindle, and means for laterally spreading said movable parts to a width greater than the width of the interior hollow space of the body of yarn of the bobbin to be applied thereto whereby to flatten said body of yarn.
25. A device for flattening the shape of a body of yarn of a round bobbin, particularly for loom shuttles and the like, consisting of a round body of yarn having a tubular interior cavity and of a holding spindle for the said body of yarn constituting a wedge-shaped element capable of being introduced into the tubular cavity of the body of yarn, and distorting the said round body of yarn transversely to flatten it.
30. A shuttle for looms, said shuttle comprising a hollowed casing having a width greater than its height, one wall of said casing being formed to provide an opening therein, a spindle for said shuttle, said spindle comprising a pair of separate and substantially identical members arranged substantially side by side in said casing and pivotally secured thereto for swinging movement to and fro through said opening, the outer side edges of said members being straight, means whereby swinging of said members outwardly of said casing brings them into juxtaposition to provide a spindle of reduced diameter to permit the application of an oversized cylindrical cop of yarn thereto, said cop having a diameter greater than the height of said casing, said means also causing said spindle members to move apart in a horizontal plane throughout substantially their entire lengths as they are swung into said casing whereby to cause the straight outer sides of said spindle to stretch said cop laterally into a flattened cop having a height less than the height of said casing.
35. A method for transforming the shape of a round body of yarn of a bobbin, particularly for loom shuttles, consisting in applying the body of yarn to a spindle, said spindle comprising a plurality of sections and having a flat cross-section and moving the sections of the spindle to increase the distance between the outer edges of the sections engaging the yarn thereby transforming the round body of yarn into a bobbin of greater width than height.
40. A method for transforming the shape of a round body of yarn of a bobbin, particularly for loom shuttles, into a bobbin wider than its height, consisting in applying a round body of yarn to a sectional spindle, in separating the sections of the spindle to spread the yarn transversely of the direction of movement of the shuttle in its travel through a shed, and simultaneously reducing the dimension of the bobbin in a direction at right angles to the aforesaid spreading movement.
45. A method for transforming the shape of a round body of yarn of a bobbin, particularly for loom shuttles, into a flat cross-section, consisting in applying the bobbin to a spindle having a flat cross-section greater than the diameter of the tubular interior cavity of the round bobbin over at least a part of the spindle length, the said spindle being operative upon application of the bobbin thereto to transform the round cross-section of the bobbin of yarn into a flat cross-section, thereby reducing the dimension of the round
50. A device for flattening a body of yarn of a round bobbin and for holding the same, particularly for loom shuttles, comprising a spindle, consisting of at least two parts, means for mounting the parts for movement longitudinally one with respect to the other and for simultaneous oscillatory movement, a body of yarn of a round bobbin, and means for subjecting the movable parts of the spindle when swung in one direction to a lateral spreading to a width greater than the interior diameter of the round body of yarn of the bobbin applied thereto to flatten the same until the height thereof is not greater than that of the shuttle.
55. A device for flattening a round body of yarn

of a round bobbin and for holding the same, particularly for loom shuttles, comprising a spindle, consisting of at least two parts movable longitudinally one with respect to the other and mounted for to and fro movement, a body of yarn of a round bobbin to be flattened being applied to the said spindle, and means whereby the swinging movement of the spindle parts when moved in one direction operates to spread the spindle parts to a degree greater than the internal diameter of the round body of yarn operated upon to flatten the same until the height thereof is not greater than that of the shuttle.

17. A device for flattening the shape of a body

of yarn of a round bobbin and for holding the same, particularly for loom shuttles, comprising a spindle, consisting of at least two parts, means for mounting the parts for oscillatory movement, means for causing the movable parts of the spindle to include an angle varying with the oscillatory movement of the parts and attaining at one end position of the oscillation maximum value determining a triangle area larger at the base than the interior base diameter of the body of 10 yarn applied to the spindle to flatten the same until the height thereof is not greater than that of the shuttle.

ABRAHAM COHEN.
